DESIGN FOR A MAGNETIC RECORDER OR SIMILAR ARTICLE

Marvin Camras, Chicago, Ill., assignor to Armour
Research Foundation, Chicago, Ill., a corpora-
tion of Illinois

Application August 26, 1944, Serial No. 115,056

Term of patent 14 years

(Cl. D26—5)

To all whom it may concern:

Be it known that I, Marvin Camras, a citizen
of the United States and a resident of the city
of Chicago, in the county of Cook and State of
Illinois, have invented a new, original, and or-
namental Design for a Magnetic Recorder or
Similar Article, of which the following is a speci-
fication, reference being had to the accompany-
ing drawing forming a part thereof.

On the drawing:

Figure 1 is an isometric view of a magnetic re-

corder showing my new design when viewed from
a point looking down at the front left corner
thereof; and

Figure 2 is an isometric view looking up at the
diametrically opposite rear corner of the mag-
netic recorder shown in Figure 1.

I claim:

The ornamental design for a magnetic recorder
or similar article, as shown.

MARVIN CAMRAS.
